UNITED STATES PATENT OFFICE.

JACOB W. MUELLER, OF BELLEVILLE, ILLINOIS, ASSIGNOR, BY MESNE ASSIGNMENTS, TO ORBON STOVE COMPANY, INCORPORATED, OF BELLEVILLE, ILLINOIS, A CORPORATION OF DELAWARE.

COMBINATION COAL AND GAS RANGE.

1,280,070.

Specification of Letters Patent. Patented Sept. 24, 1918.

Application filed May 16, 1916. Serial No. 97,856.

To all whom it may concern:

Be it known that I, JACOB W. MUELLER, a citizen of the United States, residing at Belleville, in the county of Saint Clair and State of Illinois, have invented certain new and useful Improvements in Combination Coal and Gas Ranges, of which the following is a specification, reference being had therein to the accompanying drawing.

10 This invention relates to certain new and useful improvements in combination coal and gas ranges and has for its object the provision of a range which is exceedingly compact in construction having the general 15 appearance and formation of an ordinary range with the exception of additional burner chambers under the bottom of the stove in connection with gas flues leading to the oven of the stove whereby the stove can be used with solid fuel as a coal stove, or 20 with a fluid fuel.

Another object of my invention is to provide a novel form of damper control in connection with the back flue whereby the 25 dampers will be shifted into such a position that the products of combustion passing into the oven chamber from the gas flues will be conveyed out of the oven into the back flues and under the same and then up the side flue.

30 Another object of the invention is to provide a combination coal and gas range with a pair of damper rods for controlling the dampers in such a manner that when one of the damper rods is turned, it automatically turns the other damper rod, or vice versa, so that when burning coal if it is desired to change to burning gas it is only necessary to turn one of the damper rods and when it is desired to change from gas 35 to solid fuel such as coal by turning the other damper rod, the dampers will be thrown into the proper positions for controlling the flues.

Another object of my invention is to provide 40 a valve controlled member in connection with one of the damper rods whereby the gas valve will be held closed when the damper rod is turned into position to change the stove from a gas stove to a coal stove.

45 Another object of the invention is to provide a check damper in connection with the main damper rod so as to admit air into the flue when the dampers are adjusted to convert the stove into a gas stove so as to

reduce the draft or the velocity of the products of combustion around the oven whereby the heat units will be entirely utilized.

Another and further object of the invention is to provide a combination coal and gas range with an oven having side gas flues 60 for conveying the products of combustion from the burner chambers directly into the oven chamber, said oven chamber having a damper controlled outlet affording communication with the back flue, said damper 65 being constructed to completely close the back flue when in open position so as to cause the products of combustion passing out of the oven to pass under the oven where they are reheated by being brought directly 70 into contact with plates arranged in close proximity to the burner chambers, said products of combustion passing out of the bottom flue into the side flue up the side flue into the top flue, and out the chimney 75 flue in the ordinary manner, whereby I am able to utilize the heat units to the fullest extent so as to thoroughly heat the oven chamber with a small amount of fuel.

Another and still further object of my invention is to provide a combination coal and gas range with a foraminated top under which is adapted to be arranged burners so as to provide means for cooking articles on the top thereof.

80 Other and further objects and advantages of the invention will be hereinafter set forth and the novel features thereof defined by the appended claims.

85 In the drawings,

90 Figure 1 is a perspective view of a stove constructed in accordance with my invention.

95 Fig. 2 is a longitudinal vertical section of the stove.

Fig. 3 is a transverse vertical section.

Fig. 4 is a rear view of the stove.

100 Fig. 5 is a perspective view of the dampers, damper rods and gas valve controlled means detached showing the relative position of these members when in position within a stove so as to control the flues thereof.

105 Fig. 6 is a plan view of a check damper showing the same in dotted lines in open position in order to admit air to reduce the draft when the stove is being used as a gas stove.

Fig. 7 is a horizontal section through a stove constructed in accordance with my invention showing the arrangement of the flue strip and the openings affording communication between the bottom flue and the gas flue.

Like numerals of reference refer to like parts in the several figures of the drawing. In the drawings 1 indicates a fire box, 2 10 the ash pit, 3 the oven of my improved construction of combination coal and gas range, and 4 the top which is provided with a foraminated portion 5 under which is adapted to be arranged a series of burners 15 not shown. The oven is surrounded by the ordinary coal flues so that the products of combustion from the fire box will circulate around the same in order to heat the oven chamber, said flues comprising a top flue 6, 20 a side flue 7, a bottom flue 8, and a back flue 9, the top flue being provided with the usual exit 10 affording communication with the back flue. The exit 10 is adapted to be closed by a damper 11 carried by a damper 25 stem 12 mounted in the walls of the back flue as clearly shown in Fig. 4. The back flue is provided with a flange 9' to which is connected a stove pipe collar extension 9² extending upwardly above the top of the stove 30 to which a stove pipe 13 is adapted to be connected in the ordinary manner.

In the construction thus far described, it will be seen that when the fire box 1 is filled with solid fuel such as coal, the products of 35 combustion pass over the oven through the top flue down the side flue under the oven through the bottom flue into the back flue and out the stove pipe in the ordinary manner. When the damper 11 is opened a direct draft is obtained so as to allow the 40 stove to burn quickly, and by closing the damper 11, the products are conveyed around the oven, the bottom flue being provided with a flue strip A for increasing the 45 circulation of the products of combustion under the bottom thereof in order to utilize the heat units.

The stove is provided with the usual bottom plate 14 which is formed with flanged 50 openings 15 and 16 at each side of the bottom flue 8 under which are arranged housings 17 and 18 forming burner chambers which are provided with air inlets for supplying air to the tubular burners 19 and 20 55 arranged within said burner chambers, said burners extending out through the bottom flange of the stove as shown in Fig. 1 and are provided with the usual valves 21 and 22 for controlling said burners.

Arranged over the openings 15 and 16 are 60 castings 23 and 24 forming gas flues 25 and 26 which terminate at their upper end over openings 27 and 28 formed in the end walls of the oven chamber 3 as clearly shown in 65 Figs. 2 and 3 so as to convey the products

of combustion from the burner chambers 17 and 18 directly into the oven chamber 3 in order to heat the same. The burner 19 is of greater length than the burner 20, and in order to distribute the products of combustion in the gas flue 26, I provide the same with a deflector 29 as shown in full lines in Fig. 2 and in dotted lines in Fig. 3 which conveys the products of combustion rising from the short burner 20 rearwardly 70 in order to allow the same to be distributed as they pass into the oven chamber.

The oven chamber is provided with an exit 30 affording communication with the back flue 9, said exit being closed by a damper 31 carried by a damper stem 32 mounted in the walls of the back flue, said damper being of such a size and shape that it completely closes the back flue 9 when swung into its open position as clearly 80 shown in dotted lines in Fig. 3 so as to cause the products of combustion passing out through the exit 30 of the oven 3 to pass downwardly in the back flue 9 under the oven through the bottom flue which is provided with the usual flue strip for increasing the circulation of the products of combustion in order to utilize the heat units. As the hot air and products of combustion enter the bottom flue from the back flue 95 they are reheated by radiation, by coming into contact with the side walls 33 and 34 of the bottom flue 8 as these walls are arranged directly over the burner chambers and become heated to such an extent that they throw off additional heat units by radiation which mingle with the hot air and products of combustion entering the bottom flue. The hot air and products of combustion from the bottom flue pass into the side flue through an opening B from which they 100 pass into the top flue and out through the opening 10 into the back flue.

It will be noted that the construction of tubular gas burners employed for heating the oven in the right hand gas flue is formed shorter than the burner of the left-hand flue in order to diminish the capacity thereof as I have found by experimenting that the oven will be evenly heated by employing burners of different capacity, as the side flue in which the gas flue is arranged containing the short burner receives all of the hot air and products of combustion passing out of the oven supplied from both 115 of the burner chambers.

When the stove is being used as a gas stove, I have found, that in order to obtain the best result so as to utilize all of the heat units created in the burner chambers that by providing the top of the stove with air inlets controlled by a check damper, that the velocity of the products of combustion passing into and around the oven will be 125 reduced, and while I have shown these 130

openings communicating with the top flue adjacent the exit 10, it is of course understood that they can communicate directly with the back flue without departing from the spirit of my invention. In the construction of check damper as shown, a plate 35 is employed which is seated in the reduced portion 36 formed in the top 4 over air openings 37, said plate being provided with openings adapted to register with the air openings 37 in order to admit air into the top flue and to close said opening when said check damper is shifted, said damper being provided with a hooked portion 38 for the purpose hereinafter fully described. When the check damper 35 is in open position, the damper 11, is also in open position and when the damper 11 is closed, the check damper 35 is also closed, the check damper being employed only when the stove is being used as a gas stove.

The oven is provided with the usual shelf supports above and below the inlets from the gas flues and in order to provide means for lighting the burners, I provide the bottom of the oven with openings 39 entering the gas flues 25 and 26 as clearly shown in Fig. 2 by means of which the burners can be lighted. The oven is provided with the usual door 40 mounted on horizontally disposed pivots for swinging downwardly into open position and it will be seen that by providing the interior of the oven with openings for lighting the burners, it is necessary to open the door to light the burners, thus preventing an explosion. In connection with the gas flues 25 and 26 I provide the front walls thereof with sight openings 41 in order to allow the burners to be inspected so as to ascertain whether they are burning properly.

In connection with the dampers 11 and 31, I provide a pair of damper rods 42 and 43 which are mounted vertically in suitable bearings arranged to the rear of the stove one of said damper rods being arranged to each side of the back flue 9 as clearly shown in Fig. 4. These damper rods extend up through the top of the stove and are provided with the usual handle portions 44 and 45, by means of which they are oscillated to shift the dampers 11 and 31 as will be hereinafter fully described. The damper rod 42 is preferably formed of two sections as shown in Fig. 5 connected together by bolts as shown, the lower section being provided with a bifurcated portion 46 the furcations thereof having cammed faces between which is adapted to extend the angled end 12² of the damper stem 12 so that when the handle portion 44 is oscillated, the damper 11 will be swung into vertical or closed position and when oscillated in the reverse direction will be tilted or moved into open position.

The damper rod 43 is preferably formed of three sections connected together as clearly shown, the intermediate section being provided with a pin portion 47 cooperating with the hook 38 of the check damper 35 so that when the damper rod 43 is oscillated by the handle portion 45, the check damper will be reciprocated in order to open the air inlets so as to reduce the velocity of the products of combustion passing through the oven and oven flues, when the stove is being used as a gas stove.

The opposite end of the damper stem 12 is provided with an angle portion 12² which cooperates with a cam lip 47 formed on the intermediate portion of the damper rod 43 so as to shift the damper 11 into closed position. From the construction thus far described, it will be seen that when it is desired to change the position of the dampers 35 so as to convert the stove from a coal stove to a gas stove by oscillating the damper rod 45, it will oscillate through the connection with the damper stem the damper rod 42, and when it is desired to change the dampers 35 back into the position so as to use the stove as a coal stove by oscillating the damper rod 42, the damper rod 43 will be automatically turned.

The intermediate portion of the damper rod 43 adjacent its lower end is provided with a cam lip 48 which cooperates with an angle portion 32² of the damper stem 32, said angle portion being flattened and having a cooperating cam face so that when the damper rod 43 is turned, the damper 31 will be opened and closed according to the direction in which the damper rod 43 is oscillated.

The lower section of the damper rod 43 is provided with a crank portion 49 which is provided with an opening 50 through which the angle end 51 of a controlled rod 52 is adapted to pass, said rod extending forward, under the stove and is provided with an adjustable mounted locking member 53 at its end which is adapted to embrace the valve lever 21, so as to hold the valve in closed position when the damper rod 43 is oscillated so as to throw the dampers in their proper position to use the stove as a coal stove. When the damper rod 43 is oscillated so as to throw the dampers into position for converting the coal stove into a gas stove, the operating rod 52 is reciprocated through its connection with the damper rod 43 so as to move the locking member 53 out of the path of the valve lever 21 in order to allow the gas valve to be opened and the burner lighted.

By oscillating the damper rod 43 in reverse direction the lip 47 will be moved out of the path of the angle end 12² of the damper stem 12 so as to allow the damper to be opened so as to obtain a direct draft.

for the stove when being used as a solid fuel burning stove.

In order to increase the circulation of the bottom flue of the stove, the side radiating plate 33 is provided with a series of openings 5 adjacent its rear end affording communication between the bottom flue and the gas flue 25 at the rear of the bottom flue and adjacent the bottom of the oven. By providing 10 inlet openings at this point for the bottom flue, small jets of hot air and products of combustion enter the bottom flue at the back to produce eddy-currents in the gases coming into the bottom flue from the oven 15 through the back flue, thereby increasing the circulation and radiation from the left radiating plate so as to thoroughly heat the bottom of the oven.

In the construction of oven as herein 20 shown, the right-hand burner and right-hand gas flue 26 is formed shorter than the left-hand burner chamber and flue so as to leave the opening B which affords communication between the bottom flue and the side 25 flue and by the arrangement of the flue strip A when solid fuel such as coal is being used in the stove, the products of combustion from the fire box pass into the top flue down the side flue, into the bottom flue, 30 through the opening B, around the flue strip A, and out the bottom flue into the back flue. When gas is being used, the back flue is closed at a point above the oven exit and the products of combustion passing into the oven 35 from the side gas flues circulate through the oven out the exit into the back flue, from the back flue into the bottom flue where the products of combustion and hot air are subjected to the additional jets of products 40 of combustion from the inlets C and the hot air and products of combustion are reheated by coming into contact with the radiating plates 33 and 34 forming the side walls of the bottom flue 8 and by the arrangement of 45 the flue strip A the products of combustion and hot air circulate in the bottom flue in order to thoroughly heat the bottom of the oven before they pass out through the opening B into the side flue from which they pass 50 into the top flue, and out of the exit into the back flue.

In my construction by providing the oven with side flues of different length, the shorter flue being arranged within the side 55 coal flue of the oven, I am still able to communicate the side coal flue with the bottom flue by an opening so as to allow the products of combustion from the burning coal to pass from the side flue into the bottom flue, and 60 when burning gas fuel the products of combustion are allowed to pass from the bottom flue into the side flue.

By the arrangement of the flues, I am able 65 to heat the oven thoroughly as the products of combustion in which the heat units have

been utilized are reheated as they pass through the bottom flue by coming into contact with the radiating plates so as to thoroughly heat the bottom of the oven in order to obtain the desired results.

While I have shown and described the damper rods connected in a particular manner for operating and controlling the various dampers herein shown and described for controlling the flues, I do not wish to limit myself to any particular arrangement of damper control as the same result can be obtained with a stove constructed as herein shown and described having various other forms of damper controls, and therefore I do not wish to limit myself to the particular construction and arrangement as shown, and I reserve the right to employ any and all kinds of dampers in connection with the flue arrangement without departing from the spirit 80 of my invention as defined in the claims.

While I have shown and described only one valve locking member in connection with the gas valve and damper rods, I wish to reserve the right to provide a locking device 90 for each gas valve without departing from the spirit of my invention.

From the foregoing description it will be seen that I have provided a combination coal and gas range in which the usual coal flues are still employed, and by the provision of gas flues for conveying the products of combustion from burner chambers directly into the oven chamber in connection with dampers, I am able to convert a coal 95 range into a gas range in such a manner that the oven thereof will be thoroughly heated by the products of combustion and hot air.

I claim:

1. A stove having an oven chamber surrounded by flues, said oven chamber having an outlet communicating with the back flue thereof and inlet openings in the sides thereof adjacent the bottom, gas flues communicating with said inlet openings, burner chambers arranged under said gas flues, and a damper for closing the outlet opening of said oven, said damper forming a closure for said flue.

2. A combined solid fuel and gas burning stove having an oven therein provided with the usual flues, said oven having an opening affording communication with the back flue, a damper for closing said opening, said damper forming a closure for said back flue when in open position, gas flues arranged at the sides of the oven over inlet openings formed therein, and burner chambers arranged under said gas flues.

3. A combined solid fuel and gas burning stove having an oven therein, said oven being provided with inlet openings in its sides, gas flues communicating with said inlet openings, burner chambers arranged

- under said gas flues, a back flue having an opening affording communication with the oven chamber, said opening being closed by a damper, said damper being capable of closing the back flue for causing the products of combustion to pass downwardly in the back flue under said oven.
4. A combination coal and gas range having an oven surrounded by a top flue, a side flue, a bottom flue and a back flue, gas flues arranged at the sides of the oven, burner chambers arranged under said flues, said gas flues terminating over inlet openings formed in the sides of the oven affording communication between the oven and gas flues, said oven having an opening affording communication with the back flue, and a damper for closing said opening, said damper being capable of closing the back flue when in open position.
5. A combination coal and gas range having an oven surrounded by top, side, bottom and back flues, said oven having an outlet opening affording communication with the back flue, a gas flue arranged at each side of said oven, said oven having openings affording communication between said gas flues and oven chamber, burner chambers arranged under said gas flues, and a damper for closing the outlet opening of said oven chamber, said damper forming a closure for the back flue when in open position for causing the hot air and products of combustion passing out of the oven chamber to pass downwardly under the oven and upwardly through the said flue thereof.
6. A combined solid fuel and gas burning stove having an oven therein provided with top, side, bottom and back flues, said top flue having an exit affording communication with the back flue, a damper for controlling said exit, said oven having an exit affording communication with the back flue, a damper for controlling said exit, said last-mentioned damper being capable of closing the back flue when in open position, said oven having inlet openings at the sides thereof, flues arranged over said inlet openings, burner chambers arranged under said flues, and burners arranged in said burner chambers.
7. A combination coal and gas stove having an oven chamber surrounded by top, side, bottom, and back flues, said oven chamber having inlet openings in the sides thereof, and an exit opening in the back thereof, a damper for controlling said exit opening, said damper forming a closure for the back flue when in open position, gas flues arranged over said inlet openings, and burner chambers arranged under said gas flues.
8. A stove having an oven chamber surrounded by the usual coal flues, gas flues arranged at each side of said oven chamber having communication with said oven at each side thereof, dampers for controlling the passage of products of combustion through said flues, air inlets formed in the top of said stove communicating with the flues thereof for reducing the velocity of the passage of the products of combustion through said flues, and a damper for controlling said inlet having a connection with the first mentioned dampers.
9. A combined solid fuel and gas burning stove having an oven therein, gas burner chambers arranged under said oven, gas flues extending from said chambers along-side of said oven, said oven having inlet openings affording communication with said gas flues, said oven having a damper controlled exit opening communicating with the back flue of said stove, said damper forming a closure for said back flue to cause the products of combustion to pass downwardly out of said oven and into the bottom flue thereof.
10. A combined solid fuel and gas burning stove having an oven therein surrounded by the usual flues, the top of said stove being provided with air inlets affording communication with the top flue thereof, a damper for controlling said air inlets, said top flue having a damper controlled exit affording communication with the back flue of said stove, said stove having means for conveying products of combustion directly into said oven chamber, said oven chamber having an exit affording communication with the back flue of said stove, a damper mounted in said back flue for closing said oven exit when in one position and said back flue when in another position, damper rods for actuating said dampers, and a connection between said damper rods, whereby said dampers will be automatically adjusted at the proper position for burning either solid or fluid fuel.
11. A combined solid fuel and gas burning stove having an oven surrounded by the usual flues and provided with an exit affording communication with the back flue of the stove, said oven having inlets, gas flues arranged over said inlets, burner chambers arranged under said gas flues, burners arranged in said burner chambers, and a damper mounted within said back flue for closing said oven exit when in lower position and for closing said back flue when in raised position for causing the products of combustion escaping from said oven to pass downwardly through said back flue into the bottom flue of said stove.
12. A combined solid fuel and gas burning stove having an oven therein surrounded by top, side, bottom and back flues, the top flue having a damper controlled exit affording communication with the back flue, said oven having inlet openings at the sides thereof, gas flues arranged over said inlet

- openings, burner chambers arranged under said gas flues, burners arranged in said burner chambers, said oven having an exit opening affording communication with the 5 back flue of said stove, and a damper mounted in said back flue forming a closure for said oven exit opening in one position, and a closure for said back flue when in another position.
- 10 18. A combined solid fuel and gas burning stove having an oven surrounded by the usual flues, said oven having an exit opening affording communication with the back flue thereof, the top flue of said stove having an 15 exit opening affording communication with the back flue thereof, said stove having air inlet openings communicating with the top flue thereof, dampers for said exit openings and air inlet openings, damper rods for actuating said dampers, the stem of one of said dampers forming a connection between said damper rods for causing said dampers to be alternately opened and closed to place said dampers in proper position for utilizing 20 said stove for burning solid or gas fuel.
14. A combined solid fuel and gas burning stove having an oven provided with an exit opening affording communication with the back flue of said stove, said oven having 25 inlet openings at the side thereof, gas flues arranged over said inlet openings, burner chambers arranged under said gas flues, valve controlled burners arranged in said burner chambers, a damper controlled exit 30 affording communication between the top flue and back flue, damper rods for actuating said dampers, a valve locking member arranged in the path of travel of one of said burner valves, and a connection between 35 said valve locking member and said damper actuating means.
15. A combined solid fuel and gas burning stove having an oven provided with an exit opening affording communication with the 40 back flue of said stove, a damper for closing said opening, a damper rod for actuating said damper, said oven having inlet openings, gas flues arranged over said inlet openings, burner chambers arranged under 45 said gas flues, burners arranged in said burner chambers, valves for controlling said burners, a locking member arranged in the path of travel of one of said valves, and a connection between said locking member 50 and damper actuating rod for automatically shifting said locking member out of the path of travel of said valve when said damper is in open position.
16. A combined solid fuel and gas burning stove having an oven therein provided with a damper controlled exit opening, a damper rod for actuating said damper, said oven having inlet openings, gas flues arranged over said inlet openings, burner 55 chambers arranged in said gas flues, valve controlled burners arranged in said burner chambers, a locking member arranged in the path of travel of one of said valves, and a connection between said locking member and said damper actuating rod for causing said locking member to be moved in the path of travel of said valve when said damper is in closed position and to be moved out of the path of travel of said valve when said damper is in open position.
17. A combination coal and gas range having an oven provided with an exit opening and inlet openings, means for conveying products of combustion to said inlet openings, a damper for controlling said exit opening, said damper forming a closure for the back flue of said stove when in open position for causing the escaping products of combustion from said oven to pass downwardly in said back flue under said oven.
18. A combination coal and gas stove having an oven surrounded by the usual flues, said oven having an exit opening affording communication with the back flue thereof, side gas flues arranged adjacent said oven, burner chambers arranged under said gas flues, said oven having inlet openings affording communication with said gas flues, said stove having a bottom flue with side members forming radiating plates for reheating the products of combustion passing out of said oven into the bottom flue thereof.
19. A combination coal and gas stove having an oven with inlets through which are adapted to pass the hot air and products of combustion from the burner chambers, said oven having an exit communicating with the back flue of said stove for causing the products of combustion to pass downwardly into said back flue under said oven in contact with radiating plates for reheating the products of combustion.
20. A combination coal and gas stove having an oven surrounded by the usual flues, said oven having inlets, gas flues arranged over said inlets, burner chambers arranged under said gas flues, burners arranged in said burner chambers, said oven having an exit affording communication with the back flue, and a damper mounted in said back flue forming a closure for said exit when in lowered position, and a closure for said back flue when in raised position to cause the escaping products of combustion from said oven to pass downwardly in said back flue under the oven.
21. A combination stove and gas range having an oven chamber surrounded by the usual coal flues, gas flues arranged at each side of said oven and communicating with said oven, one of said gas flues having openings at its rear end affording communication with the bottom flue of said stove, and a

damper for closing the back flue to cause the products of combustion passing out of the oven chamber to pass under the oven.

22. A combination coal and gas range having an oven chamber provided with the usual coal flues, said oven chamber having an exit opening communicating with the back flue of said stove, gas flues arranged at each side of said oven chamber having openings communicating with said oven chamber, one of said gas flues having openings communicating with the bottom flue of said stove, and a damper forming a closure for said oven exit in one position, and a closure for the back flue in another position to cause the products of combustion escaping from the oven chamber to pass downwardly into the bottom flue.

23. A stove having an oven chamber provided with the usual coal flues including top, side, bottom, and back flues, side gas flues having openings communicating with said oven chamber, said oven chamber hav-

ing an outlet communicating with the back flue, and means for causing the products of combustion passing out of said outlet to pass downwardly in said back flue under said oven and out the side flue thereof.

24. A stove having an oven chamber surrounded by the usual coal flues, gas flues arranged at each side of said oven having openings communicating therewith, burner chambers arranged under said gas flues, said oven chamber having an outlet communicating with the back flue, means for closing said back flue to cause the products of combustion to pass into the bottom flue of said stove, and means for reheating the products of combustion as they pass through the bottom flue thereof.

In testimony whereof I hereunto affix my signature in the presence of two witnesses.

JACOB W. MUELLER.
